(57) **CLAIM**

The ornamental design for a wireless communication device PC card, as shown and described.

DESCRIPTION

FIG. 1 is a perspective view of a wireless communication device PC card with the upper compartment shown extended. FIG. 2 is a top view of the wireless communication device PC card of FIG. 1.

FIG. 3 is a side view of the wireless communication device PC card of FIG. 1.

FIG. 4 is a bottom view of the wireless communication device PC card of FIG. 1.

FIG. 5 is a proximal end view of the wireless communication device PC card of FIG. 1; and,

FIG. 6 is a distal end view of the wireless communication device PC card of FIG. 1.

The broken lines are for purposes of illustration only and form no part of the claimed invention.
